Charles L. Robertson

CHARLES L. ROBERTSON, OF PROVIDENCE, RHODE ISLAND.

Letters Patent No. 88,810, dated April 13, 1869.

IMPROVEMENT IN TABLE-CUTLERY.

The Schedule referred to in these Letters Patent and making part of the same.

To all whom it may concern:

Be it known that I, CHARLES L. ROBERTSON, of the city and county of Providence, in the State of Rhode Island, have invented a new and useful Improvement in Handles for Table-Cutlery, and like purposes; and I do hereby declare that the following specification, taken in connection with the drawings making a part of the same, is a full, clear, and exact description thereof.

Figure 1 is a view, in perspective, of a table-knife with my improved handle.

Figure 2 is a side view of one of the halves of the paper "foundation" of the handle.

Figure 3 is a sectional view through the blade, the tang, and the handle.

The purpose of my invention is to produce a handle for table-cutlery, and other articles, by the employment of a combination of materials and processes, resulting in the production of a new manufacture for such purpose.

I prepare, in the first place, a foundation for a handle, which is to be composed wholly or principally of paper, or some one of the manufactures from paper-stock, as, for example, card-board, junk-board, binders'-board, or straw-board.

If some one of these, or similar manufactures, is employed, the foundation for the handle should be made in two halves, as seen at A, fig. 2, by being cut by any suitable machinery, into the proper form for the subsequent operations.

Several thicknesses of thin paper, or paper-board, may be employed, instead of one thickness, if preferred, but in such case the several thicknesses should be glued, or, by some adhesive material, secured together throughout their length; and if additional strength is required, strips of cloth may be placed between the thicknesses of paper, and also the paper foundation may be enveloped with a wrapping of muslin, or other cloth of thin texture.

The halves of the handle so prepared, may then be accurately shaped, by being subjected to pressure between metallic dies, and during this process any ornamental design or configuration may be given to or embossed upon them, which taste or fancy may indicate, provided it is not of a character to interfere with the completion of the manufacture, by the finishing-process hereafter described.

In order that the action of the dies may be complete, the foundation should be dampened sufficiently to enable it to take readily the impression of the dies, and adapt itself to their form.

After the halves of the handle have been so made, or contemporaneous with the operation of finishing their form by dies, the blade of the knife, or other article to which such handle is to be attached, is con-

nected with the handle in the manner usually practised in the manufacture of table-cutlery with hard-rubber handles.

The tang of the blade is made barbed, as shown at a, fig. 3, so that the two halves of the handle will, when pressed together, and their surfaces in contact spread with a suitable adhesive composition, by the sinking of the tang into the material forming the halves of the handle, become firmly attached thereto, and the two halves of the handle will at the same time be joined together.

Instead of manufactured paper, or paper-board, paper-pulp may be used to form a handle, in which case it will be well to have the mass mixed with glue, or some adhesive compound, to give additional stiffness to it when dried.

The manner of moulding the material in such state, is substantially the same as that employed when plastic rubber is employed.

After the paper or paper-stock handle has been made and affixed to the article to which it belongs, in the manner above indicated, or in some other similar way, and become thoroughly dry, the next operation for the completion of the manufacture, is to cover the whole exterior surface of the foundation with a suitable japanning, or enamelling-composition.

I prefer to make use, for this purpose, of the composition for which Letters Patent were granted to me, April 13, 1867, to which reference may be had, and develop the same into a glossy surface, by the application of heat, as described in that patent, inasmuch as I consider it the best for the purpose, but I do not confine myself to the use of the same.

Any japanning, or enamelling-composition which is of sufficient strength and consistency to furnish an outside protecting-covering to the foundation, and be impervious to water, and resist its action when heated, will answer the end, irrespective of the question whether such composition will, upon application of heat, develop a lustrous surface or not.

My invention can also be employed in the manufacture of slabs, or blanks for the handles of pocket-cutlery, in imitation of hard-rubber slabs for the same purpose.

By the employment of the invention above described, an inexpensive, and, in itself, unsuitable material, may be made use of as the foundation for handles for articles of different kinds, which, when coated with a composition, as above described, possessing the property of rendering the foundation impervious to moisture, and shielding it from the effects of ordinary wear, results in a new and useful manufacture possessing great beauty.

Having thus described my invention,
I wish it to be understood that it does not reside in,

nor do I claim the manner in which the foundation is moulded, whether made from paper, or from pulp.

Neither do I claim as new, the means by which the handle is attached to the tang; but

What I do claim as my invention, and desire to secure by Letters Patent, is—

Handles for table-cutlery, and other articles made, wholly or principally of paper, or paper-stock, as a

foundation, and surfaced, for a protection and finish, with a japanning, an enamelling, or equivalent composition, the same being a new manufacture, substantially of the character described.

CHARLES L. ROBERTSON.
